UNITED STATES PATENT OFFICE.

GERALD DEAKIN, OF ANTWERP, BELGIUM. ASSIGNOR TO WESTERN ELECTRIC COMPANY, INCORPORATED, OF NEW YORK, N. Y., A CORPORATION OF NEW YORK.

POWER-TRANSMITTING MECHANISM.

Application filed May 2, 1922. Serial No. 557,818.

To all whom it may concern:

Be it known that I, GERALD DEAKIN, a citizen of the United States, residing at Antwerp, in the Kingdom of Belgium, have **5** invented certain new and useful Improvements in Power-Transmitting Mechanisms, of which the following is a full, clear, concise, and exact description.

This invention relates to power transmitting mechanisms and is directed, more particularly, to an intermittent driving device which is especially adapted for use in driving rotary switches such as are employed in certain types of automatic telephone **15** exchanges.

One type of rotary switches to which the invention is applicable is generally known in telephone parlance as "sequence switches"—which derive their name from the fact **20** that their function is to open and close a plurality of circuits sequentially to control in proper order the operations of the several switching devices and adjunct apparatus which are employed in the mechanical establishment of connections between telephone **25** subscribers. In order that the time required for the completion of a telephone connection may be as short as possible, it is necessary that every piece of apparatus involved shall **30** operate as rapidly as possible. The sequence switches are not only required to operate speedily, but in each cycle of operation consisting usually of only one revolution, are required to make many stops, each in a definite angular position and it is therefore evident that some provision must be made to **35** quickly and accurately stop them in each position.

It is an object of this invention to provide **40** braking means for quickly and accurately stopping the movement of a relatively high speed rotating device such as a sequence switch, which will insure against overthrow, without inducing excessive wear.

Another object of the invention is the provision of means whereby wear on the braking **45** means may be compensated for.

In accordance with the above objects the invention consists in the combination of **50** driving and driven members normally held out of engagement by a spring-pressed roller, and electromagnetic means for engaging said members, with a stop, against which the driven member is forced by the spring-pressed roller immediately upon the deen-

ergization of the electromagnetic means and the disengagement of the driven member from the driving member. The stop is rendered adjustable to compensate for wear and the spring-pressed roller is mounted to enable an adjustment of the frictional retarding force to be applied by the stop. The pole pieces of the electromagnetic means are placed in magnetic proximity respectively to the driving and driven members and are **60** adjustable for the purpose of regulating the airgaps in the magnetic circuit.

Still other features will be apparent in the details of construction as set forth in the following description and appended **65** claims.

The accompanying drawing illustrates the preferred form of the invention, wherein Fig. 1 is a side elevation partly in cross section of a mechanism in accordance with this **70** invention and includes a fragmentary showing of a sequence switch. Fig. 2 is a view in cross section on the horizontal line C—D of Fig. 1 of the mechanism and Fig. 3 is a detail view partly in section taken along the **75** line A—B of Fig. 2.

The continuously rotating driving shaft **80** 1 is mounted by means of adjustable ball bearings 2 upon a portion 3 of the framework of the switch, which framework is secured to a supporting member 4, a portion **85** only of which is shown. The driving disc 5 carries a collar 6 of considerable length, bored to fit around the shaft 1 and secured thereto by means of set screw 7. The edge **90** of the disc 5 is bevelled as shown. The portion 3 of the framework of the switch is shaped as shown in Fig. 2 and is provided with a projecting portion 8. This portion **95** 8 forms a support for a member 9, two arms of which fit around the portion and are secured on either side thereof by set screws 10 in such a manner that the member 9 is pivoted upon the frame 3 and may be rocked upon the said screws 10 as a pivot. The **100** driven disc 11 consists of an outer ring 12 secured to an inner ring 13 located around or otherwise secured to the shaft 14 by means of radially extending arms 15. This construction permits the outer edge of the ring 12 to be pulled down slightly, the edge of ring 12 being normally positioned as shown in Fig. 1 in close proximity to the outer edge of the disc 5 so that only a slight **105** air gap exists therebetween. The outer **110**

edge of the driven disc 11 is turned up as shown in Fig. 1 so that it lies substantially parallel to the bevelled edge of the driving disc 5. With this construction a flexible driven disc is obtained, the edge of which may be moved down slightly with relation to the center portion into engagement with the driving disc 5. The member 9 has formed integrally therewith a longitudinally extending arm 16 which extends parallel with and above the upper surface of the portion 8 of the framework 3. The end of said arm is provided with a depression or hole 17 which is engaged by the upper rounded end of a screw 18, the lower end of which is threaded and is adapted to screw into the framework 3. The screw 18 has a knurled enlarged portion 19. The lower portion of the member 9 has secured thereto by means of screws 20, a flat spring 21, the outer bifurcated end 22 of which is turned up and carries a roller 23. The roller 23 is pressed by means of the spring 21 into engagement with the under surface of the driven disc 11.

Passing through a portion of the framework 3 extending above the driven disc 11 is a screw 24, the lower end of which carries a brake block or stop 25, the lower surface of which engages the upper surface of the driven disc 11. The screw 24 carries a locking nut 26.

Secured to a portion 27 of the framework by means of screws 28 are the spools 29 of an electromagnet, the cores of which extend parallel to and below the driving and driven discs. The free ends of the cores are surrounded by members 30 of iron. Screwed into the upper side of the members 30 are adjustable pole pieces 31, the heads of which are provided with small holes around the circumference for the reception of a spanner wrench in order to permit the pole pieces to be screwed into the members 30. The pole pieces 31 are locked in position by means of screws 32. The upper surfaces of the pole pieces 31 are arranged parallel with the under surfaces of the discs and their positions are such that one pole piece is under a portion of the driving disc 5, while the other is under a portion of the driven disc 11. The terminals of the windings of the magnet are secured to soldering terminals 33.

The shaft 14 in the present instance is that of a sequence switch, such as shown in United States Patent No. 1,127,808, issued February 9, 1915 to J. N. Reynolds and C. F. Baldwin. In Fig. 1 there is shown a fragment of such a switch consisting of two circuit controlling discs or cams 34, each of which is associated with a set of contact springs or brushes 35. There is also shown a corrugated centering disc or cam 36 against which a spring-pressed roller

27 bears. Disc 36 and roller 27 are provided to insure that the switch will stop in definite angular positions and in switches which operate at relatively low speeds, this provision is relied upon entirely. But it will be seen that with greatly increased speeds, the probability of the switch continuing in motion after the driving force is disengaged is greatly increased. Inasmuch as the sequence switch per se is not a part of the present invention, it is not thought necessary to give a more complete description thereof, but for such a description reference may be had to the aforementioned patent.

The operation of the device is as follows: When it is desired to drive the shaft 14 the electromagnet is energized and the disc 11 is attracted into engagement with the driving disc 5 against the tension of the spring 21. The upper surface of the disc 11 thereby moves away from the under surface of the brake block or stop 25 while the under surface of the disc 11 remains pressed into engagement with the roller 23. The driven disc 11 is thus free and is driven together with shaft 14 and cams 34 and 36 by power from the driving disc 5 and rotates at a high rate of speed causing the roller 23 to rotate idly.

When it is desired to stop the movement of the switch the electromagnet is deenergized and the upper surface of the driven disc 11 is forced by means of the spring 21 and the roller 23 against the under surface of the brake block 25. The friction between the block 25 and the upper surface of the disc 11 causes the latter to be immediately brought to rest. It has been found that this arrangement is exceedingly efficient in practice, the sequence switch in moving even at a high rate of speed being brought to rest accurately in the desired position. The tension exerted by the spring 21 to force the roller 23 against the disc 11 is easily adjusted by turning the screw 18 which causes the member 9 to rock slightly about the pivot screws 10 so as to tend to move the roller 23 towards or away from the inner surface of the driven disc 11. The position of the brake block 25 may also be adjusted with respect to the upper surface of the driven disc 11 by turning the screw 24 which may be locked in the position to which it is set by means of the locking nut 26. By this arrangement wear on the brake block 25 may be compensated for and the air gap between the driving and driven disc adjusted.

The air gap between the edges of the driving and driven discs may also be readily adjusted to any desired dimension by moving the collar 6 relatively to the shaft 7. Further, the position of the pole pieces 31 with respect to the discs may be varied by screwing these pieces into or out of the cores 30,

the pole pieces being locked in any desired position by means of the said screws 32.

While one specific embodiment of the invention has been described, this has been given by way of example, and it will be fully understood that the particular manner of carrying out the invention may be modified in many ways without departing from the spirit thereof which consists essentially of 10 a mechanical brake associated with the driven member adapted when operated to arrest this member and to hold it against movement when at rest.

What is claimed is:

- 15 1. In a driving mechanism, a rotatable driving member, a rotatable driven member normally disengaged from said driving member, means for intermittently flexing one of said members into driving engagement with the other, and means for frictionally engaging said driven member upon its release from said driving member operable to stop the rotation of said driven member.
- 20 2. In a driving mechanism, a rotatable driving member, a rotatable driven member normally disengaged from said driving member, means for intermittently flexing one of said members into driving engagement with the other, and an adjustable stop for frictionally engaging said driven member upon its release from said driving member to stop the rotation of said driven member.
- 25 3. In a driving mechanism, a rotatable driving member, a rotatable driven member normally disengaged from said driving member, means for flexing said driven member into driving engagement with said driving member, a stop for frictionally engaging said driven member upon the release of the latter from said driving member, and spring means for forcing said driven member against said stop.
- 40 4. In a driving mechanism, a rotatable driving member, a rotatable driven member normally disengaged from said driving member, means for flexing said driven member into driving engagement with said driving member, a stop for frictionally engaging said driven member upon the release of the latter from said driving member, and means opposed to said stop for forcing said driven member into engagement with said stop.
- 45 5. In a driving mechanism, a rotatable driving member, a rotatable driven member normally disengaged from said driving member, means for flexing said driven member into driving engagement with said driving member, a stop for frictionally engaging said driven member upon the release of the latter from said driving member and adjustable spring-pressed means for forcing said driven member into engagement with said stop.
- 50 6. In a driving mechanism, a rotatable driving member, a rotatable driven member normally disengaged from said driving member, means for flexing said driven member into driving engagement with said driving member, a stop for frictionally engaging said driven member upon the release of the latter from said driving member, and means opposed to said stop for forcing said driven member into engagement with said stop.
- 55 7. In a driving mechanism, a rotatable driving member, a rotatable driven member normally disengaged from said driving member, means for flexing said driven member into driving engagement with said driving member, a stop for frictionally engaging said driven member upon the release of the latter from said driving member and adjustable spring-pressed means for forcing said driven member into engagement with said stop.
- 60 8. In a driving mechanism, a driving member and a driven member normally disengaged, an electromagnet for actuating one of said members into driving engagement with the other of said members, said electromagnet having a magnetic circuit including both of said members, and an adjustable pole piece on said electromagnet whereby the magnetic gap between one of said members and said pole piece may be varied.
- 65 9. In a driving mechanism, a driving member and a driven member normally disengaged, and an electromagnet for actuating one of said members into driving engagement with the other of said members, said electromagnet having its pole pieces in magnetic proximity respectively to said driving and driven members.
- 70 10. In a driving mechanism, a driving member and a driven member normally disengaged, an electromagnet for actuating one of said members into driving engagement with the other of said members, said electromagnet having a magnetic circuit including both of said members, and adjustable pole pieces on said electromagnet whereby the magnetic gaps between said members and said pole pieces may be varied.
- 75 11. In a driving mechanism, a driving member and a driven member normally disengaged, an electromagnet for actuating one of said members into driving engagement with the other of said members, said electromagnet having a magnetic circuit including its core and both of said members, and adjustable pole pieces for said electromagnet comprising members threaded into the ends

70 75 80 85 90 95 100 105 110 115 120 125 130

6. In a driving mechanism, a rotatable driving member, a rotatable driven member normally disengaged from said driving member, means for moving said driven member into driving engagement with said driving member, an adjustable stop for frictionally engaging said driven member upon the release of the latter from said driving member, spring-pressed means for forcing said driven member into engagement with said stop, and means for adjusting the tension of said spring-pressed means.

7. In a driving mechanism, a rotatable driving member, a rotatable driven shaft, a driven disc resiliently mounted on said shaft so that its peripheral portion is yieldable in a plane at right angles to the plane of rotation of said shaft, a stop against which said driven disc normally rests, said stop being adapted to function as a brake for said driven disc, electromagnetic means for forcing said driven disc into driving engagement with said driving member and out of engagement with said stop, and a spring-pressed roller bearing on said driven disc operable to force said disc into engagement with said stop upon deenergization of said electromagnetic means.

8. In a driving mechanism, a driving member and a driven member normally disengaged, an electromagnet for actuating one of said members into driving engagement with the other of said members, said electromagnet having a magnetic circuit including both of said members, and an adjustable pole piece on said electromagnet whereby the magnetic gap between one of said members and said pole piece may be varied.

9. In a driving mechanism, a driving member and a driven member normally disengaged, and an electromagnet for actuating one of said members into driving engagement with the other of said members, said electromagnet having its pole pieces in magnetic proximity respectively to said driving and driven members.

10. In a driving mechanism, a driving member and a driven member normally disengaged, an electromagnet for actuating one of said members into driving engagement with the other of said members, said electromagnet having a magnetic circuit including both of said members, and adjustable pole pieces on said electromagnet whereby the magnetic gaps between said members and said pole pieces may be varied.

11. In a driving mechanism, a driving member and a driven member normally disengaged, an electromagnet for actuating one of said members into driving engagement with the other of said members, said electromagnet having a magnetic circuit including its core and both of said members, and adjustable pole pieces for said electromagnet comprising members threaded into the ends

of the core of said electromagnet whereby the magnetic gaps between said members and said pole pieces may be varied.

12. In a driving mechanism, a driving member and a driven member normally disengaged, a stop against which said driven member normally rests, said stop being adjustable toward and away from said driven member and adapted to function as a brake for said driven member, means for forcing said driven member into driving engagement with said driving member, a pivotally

mounted spring arm, a roller pivoted on said spring arm and bearing against said driven member under the tension of said spring arm and tending to force said driven member against said stop, and a micrometric adjustment device for varying the pressure of said roller against said driven member. 18

In witness whereof, I hereunto subscribe my name this 13th day of April A. D., 1922. 20

GERALD DEAKIN.
